WALDO SHELDON, OF SOUTH NORWALK, CONNECTICUT, ASSIGNEE TO SHELDON
MACHINERY CORPORATION, OF NEW YORK, N. Y., A CORPORATION OF NEW YORK

WELL DRILLING APPARATUS

Application filed August 11, 1928. Serial No. 293,950.

This invention relates particularly to the hoist mechanism or so-called "draw works" of rotary well drills.

Special objects of the invention are to provide a hoist which can be operated at both high and low speeds and which can be shifted without stopping from one speed into the other; in which the high speed drive will take up the load from the low speed drive gradually and without jerk or jar, and in which the return from high speed to low speed may be similarly effected; to provide an extra power take off, which may be conveniently used as required, as for operation of a bailing reel or other purposes; and to provide the hoist mechanism in a simple, sturdy construction with the parts readily accessible and the whole practical and efficient for the purposes intended.

The various novel features of construction, combination and relations of parts by which the foregoing and other desirable objects are attained will be clear from the following specification, in connection with the accompanying drawings forming part of the same.

The drawings referred to are illustrative of one commercial embodiment of the invention, but as will be clear from the broad scope of the claims, the structure may vary without departure from the true spirit and scope of the invention.

Fig. 1 is a side elevation of a complete drill with an embodiment of the hoist mechanism of the present invention incorporated therein; Fig. 2 is a plan view of the machine with the engine shaft removed between the sprockets 15, 16 to show the main drive shaft and two speed clutches below the same; Fig. 3 is a transverse sectional view of the drum and other parts of the hoist mechanism as taken on line 3—3 of Fig. 1. Fig. 4 is a broken detail of the brake band mounting.

The machine illustrated is of the type covered in Sheldon Patent 1,684,087, June 28, 1927, and comprises a rotary table 5 convertible from power feed to straight rotary operation, mounted on one end of a sled frame 6, with hoist mechanism 7 mounted on the intermediate portion of the frame between

the table at one end and the engine 8 at the opposite end, the latter being shown as of the inverted V cylinder type covered in Sheldon Patent 1,670,596, May 22, 1928. The drive from the motor shaft 9 is shown as by way of sprocket chain connections 10' to the two speed clutches 10, 11 on the main drive shaft 12, which extends longitudinally of the frame beneath the hoist mechanism to the table at the far end of the frame, where it carries a bevel pinion 13 in mesh with the bevel gear 14 on the table. The difference in speed for clutches 10 and 11 is accomplished in the illustration by having one sprocket gear 15 on the motor shaft larger than the other sprocket gear 16 and by having a jaw member 17 keyed on the main shaft between the jaw clutch members 10 and 11 and movable into coupled engagement with either by a pivoted shifter lever 18 operated by link 19 from a rocker arm 20 on rock shaft 21, having at the outside of the frame a clutch lever 22. A clutch 23 is shown interposed in the line shafting and as operable from a foot pedal 24 and linkage connections 25 and 26, so that the table may be cut into and out of operation as required.

The drum of the hoist is indicated at 27 and is shown in Fig. 3 as keyed at 28 on a shaft 29 which is journalled in anti-friction bearings 30 removably bolted at 31 on the horizontal steps or shoulders 32 of substantially L-shaped side frames 33 mounted on the side sills of the main frame. The upper portions of the L-shaped side frames are shown as braced and steadied by angular braces 34 extending from the shoulders 32 over the drum bearings to the upper vertical portions of the side frames and bolted in place at their lower and upper ends at 35, so that they may be readily removed from over the drum bearings when for any reason the drum is to be unmounted. The drum is shown as having brake flanges 36 and 37, bolted to the opposite end heads of the same, with which cooperate the brake bands 38, 39, controlled by an equalizer bar 40 and link 41 connected with the cranked shaft 42 having an operating lever 43.

The drive of the drum is effected through

a ring gear 44 bolted to the inner face of the brake flange 37 in a space between that flange and the adjacent head of the drum, Fig. 3. Engaged with this drum gear, below the drum is a low speed drive pinion 45 on a short cross-shaft 46 carrying at its inner end a bevel gear 47 in driven engagement with a bevel pinion 48 on the main shaft 12 and controlled by a clutch 49. This cross shaft is shown journaled at its outer end at 50 on the side sill of the frame and as journaled at its inner end at 51, in the bearing member 52 for the main shaft, this construction insuring proper meshing relation of the two bevel gears. The low speed drive pinion 45 is indicated as controlled by a slideable jaw clutch member 53 keyed on the cross shaft and shiftable into and out of driving relation with the pinion by means of a shifter 54 operated by linkage 55 from the low speed clutch lever 56.

The high speed drive of the drum is effected in the present disclosure by means of a pinion 57 in mesh with the drum gear 44 and mounted on the cathead shaft 58, which is journaled in bearings 59 on the upper vertical portions of the side frames in a position to the rear of a vertical center line (Fig. 1) intersecting the centers of the drum and low speed gear axes. This arrangement of the gears, as will be clearly apparent in Fig. 1, in the assembling of the machine enables the drum to be "rolled" or slid into and out of mesh with the drive gears without disturbing the latter and the mounting of the drum on the horizontal shelves 32 which are wholly uncovered when the braces 34 are removed is a further aid in such mounting and unmounting operations. Control of the high speed drive is effected in the present disclosure by a heavy duty friction clutch 60 mounted on the cathead shaft and controlled by a shifter fork 61 on rock shaft 62 journaled in the upper portion of the frame and carrying a hand lever 63. Dual control of this high speed clutch is shown as provided for by having a link 64 connected with clutch lever 63 at the upper end and extending down to a foot pedal 65.

The cathead shaft 58 is shown as driven by means of a sprocket pinion 66 thereon engaged by a sprocket chain 67 running over a sprocket gear 68 on the outer end of the cross shaft 46, the proportions of such gearing being such as to impart the desired high speed to the drum when pinion 57 is clutched in driving relation to the drum gear. The catheads 69 are shown on the outer ends of the cathead shaft in position for convenient use of the same. As shown particularly in Figs. 2 and 3, the sprocket drive for the catheads and both the low speed and high speed drum gearing are all located on the far side of the machine, away from the drill-

ers station adjacent the various controls described.

To provide a power take off for driving a bailing reel or other purpose, a sprocket 69' is shown loosely mounted on the driven sleeve 70 of the high speed clutch and adapted to be cut into service when required by a jaw clutch member 71 keyed on said sleeve at 72 and shiftable by lever 73 from the position shown in Fig. 3, where it is locked in driving relation to the high speed pinion 57 over into driving relation to the take off sprocket 69'. This take off drive instead of being of the chain sprocket type may be of any other standard form of drive and the clutch by which the same is cut into and out of service may be of the jaw type disclosed, or any other form suited to the desired control. The operation as shown, by which the high speed drum driving gear is cut out of service when the power take off is brought into service is particularly desirable, preventing possible confusion between operation of the drum and operation of the power take off. At the same time, if required, the drum may be operated through the low speed gearing under control of clutch 53.

The engine is shown as controlled by a combination throttle and reversing valve 74 actuated by linkage 75 brought to a throttle and reversing lever 76, at the same side of the machine as the other controls, so that all operations may be governed from the one station.

With the invention disclosed, the drill may start, stop, reverse and drive the hoist or the table, or both at different speeds in either direction and may start the hoist with the low speed gearing and, without stopping, take up the load with the high speed gearing gradually and without jar or jerk. Conversely, the shift from high speed drive back to the low speed hoist operation may be effected easily and smoothly by utilizing the characteristic operations of the frictional and positive clutches in the high speed and low speed drives. Both drive gears work on the same drum gear, so that only one drum gear is necessary, and this use of only one drum gear enables the spooling portion of the drum to be made longer, for the same space between the side frames, than where two separate drum gears have to be provided. The mounting of the drum bearings on steps on the side frames and the placing of the driving gear axes behind a diametrical line passing through the drum axis, so that the drum can be slid along the bearing shelves and in fact, rolled out of and into engagement with the drive gears are important structural advantages. The bracing of the upper ends of the side frames and the quick removability of the braces steadies the cathead structure and accomplishes this without materially interfering with the removability of the drum. The

driving of the drum from below at one speed and from above at a different speed provides a desired balance both from structural and power standpoints. The high speed clutch 5 on the cathead shaft gives a fly-wheel effect, which aids the operation of this shaft and of the drum as well. The clutch 49 on the main shafting enables the drum and cathead gearing to be entirely cut out of operation 10 when only the table is being used. Clutch 71 on the cathead shaft enables the drum to remain stationary while the power take off 69' is being utilized for power purposes. It will be evident that the various other controls 15 disclosed enable full and efficient utilization of the machine.

The brake band setting shaft 42 is shown in Figs. 1 and 3 as journaled in the side frames 33 and Figs. 3 and 4 show how the 20 fixed ends of these bands are anchored to the side frames by means of the inwardly projecting lugs or brackets 77 on these frames with which the bolts 78 of the dead ends of the bands are connected. Thus the bands are 25 entirely supported and operated by the side frames and as the drum is journaled on these same side frames constant alinement of the brake drums and brake bands is assured and the bands may be kept in more effective condition. 30

The high speed clutch may be of the positive type if desired, but it is considered preferable at this time to use the impositive or frictional form of clutch so that it can be 35 thrown in to gradually take the load off the low speed gearing. The operation of this clutch is aided by having the foot pedal connection 64, 65 to aid the hand lever 63, the operator using either the lever or foot 40 pedal or both, the pedal being desirable in throwing in the clutch which necessarily is of heavy construction and may require considerable power to close it.

The low speed clutch 53 is shown in Fig. 45 2 as of the spiral jaw type to enable an "over-running" and uncoupling action for automatically uncoupling this clutch as the frictional clutch is engaged to kick out the load. Thus the low speed clutch is made to 50 automatically "kick out" as the friction high speed clutch comes into action. With this high speed frictional clutch in control, the driller or operator may uncouple the drive to the drum at any time without stopping 55 the engine and without reversing the engine as has been necessary heretofore where square jaw or positive clutches were used in the high speed drive.

What is claimed is:

60 1. In apparatus of the class disclosed, a hoisting drum, low speed and high speed drive gearing for the same, said low speed gearing including a positive clutch and the high speed gearing including an impositive clutch, with means for independently and

conjointly controlling said clutches to enable the high speed gearing to take the load off the low speed gearing and to return the load to the low speed gearing, both while the machine is running, said low speed and high speed gearing further including shafting above and below the drum on which the clutches are mounted, with gears on said shafting, a drum gear meshed by both said gears and in which said shafting includes shafts both located to one side of a diametrical axis of the drum so that said drum may be removed without disturbing said shafts. 70

2. In apparatus of the class disclosed, a hoisting drum, low speed and high speed drive gearing for the same, said low speed gearing including a positive clutch and the high speed gearing including an impositive clutch, with means for independently and conjointly controlling said clutches to enable the high speed gearing to take the load off the low speed gearing and to return the load to the low speed gearing, both while the machine is running, said low speed and high speed gearing further including shafting above and below the drum on which the clutches are mounted, with gears on said shafting, a drum gear meshed by both said gears and in which said shafting includes shafts both located to one side of a diametrical axis of the drum so that said drum may be removed without disturbing said shafts and said drum being mounted on shelves open to one side to admit of such removal of the drum. 80

3. In apparatus of the class disclosed, a hoisting drum, low speed and high speed drive gearing for the same, said low speed gearing including a positive clutch and the high speed gearing including an impositive clutch, with means for independently and conjointly controlling said clutches to enable the high speed gearing to take the load off the low speed gearing and to return the load to the low speed gearing, both while the machine is running, said low speed and high speed gearing further including shafting above and below the drum on which the clutches are mounted with gears on said shafting, a drum gear meshed by both said gears and in which said shafting includes shafts both located to one side of a diametrical axis of the drum, so that said drum may be removed without disturbing said shafts and said drum being mounted on shelves open to one side to admit of such removal of the drum and braces for the supporting structure of the drum extending over the open sides of said shelves but readily removable to enable the quick removal of the drum. 100

4. In a hoist of the character disclosed, substantially L-shaped side frames providing upright portions and open bearing shelves, a drum having bearings removably mounted on said shelves, removable braces extending from the shelves over the drum bearings to 110

the upright portions of the L-frames, shafts below the bearing shelves and projecting to the outside of the upright portions of the L-frames and gears on said shafts and drum 5 for operation of the drum.

5. In apparatus of the character disclosed, a main drive shaft, a cross-shaft driven thereby, a drum, drive gearing from said cross shaft to said drum, a cathead shaft, drive 10 gearing from said cathead shaft to the drum and drive gearing from the cross shaft to said cathead shaft.

6. In apparatus of the character disclosed, a main drive shaft, a cross-shaft driven 15 thereby, a drum, drive gearing from said cross shaft to said drum, a cathead shaft, drive gearing from said cathead shaft to the drum, drive gearing from the cross shaft to said cathead shaft, said drive gearings including clutch means by which the drive of 20 the drum from the cross shaft and from the cathead shaft may be independently controlled.

7. In apparatus of the character disclosed, 25 a main drive shaft, a cross-shaft driven thereby, a drum, drive gearing from said cross shaft to said drum, a cathead shaft, drive gearing from said cathead shaft to the drum, drive gearing from the cross shaft 30 to said cathead shaft, said drive gearings including clutch means by which the drive of the drum from the cross shaft and from the cathead shaft may be independently controlled and power take off gearing and control means therefor on the cathead shaft.

8. In apparatus of the character disclosed, a main drive shaft, a cross-shaft driven thereby, a drum, drive gearing from said cross shaft to said drum, a cathead shaft, 40 drive gearing from said cathead shaft to the drum, drive gearing from the cross shaft to said cathead shaft and clutch means by which the drive of the cross shaft from the main power shaft may be controlled.

45 9. In apparatus of the character disclosed, the combination of a hoisting drum, low speed drive gearing for said drum and including a clutch, high speed drive gearing for said drum and including a clutch, means for controlling said low speed and high speed clutches and said low speed drive clutch being of the over-running automatically uncoupling type to automatically uncouple the low speed gearing under the increased speed operation effected by the coupling action of the high speed drive clutch, a power take-off and controlling clutch means therefor enabling use of said power take-off when the low and high speed 55 drive gearings are not in use for driving the drum.

10. In hoist mechanism of the character disclosed, a hoisting drum, shafts above and below said drum, drive gearing from said 60 shafts to the drum and arranged to drive the

drum at different speeds, clutch means for independently controlling said two runs of drive gearing, a power take-off on the shaft above the drum, clutch means for coupling said power take-off in driven relation with 70 the shaft and means for driving said shaft and whereby the drum may be selectively driven through either the high speed or low speed gearing, or the drum be permitted to rest when the power take-off is in use.

In testimony whereof I affix my signature.

WALDO SHELDON.
